CLAIM

The ornamental design for a light-emitting diode package, substantially as shown and described.

DESCRIPTION

FIG. 1 is a front view of a light emitting diode package according to our new design;

FIG. 2 is a rear view of a light emitting diode package according to our new design;

FIG. 3 is a left side view of a light emitting diode package according to our new design;

FIG. 4 is a right side view of a light emitting diode package according to our new design;

FIG. 5 is a top view of a light emitting diode package according to our new design;

FIG. 6 is a bottom view of a light emitting diode package according to our new design;

FIG. 7 is a perspective view of a light emitting diode package according to our new design; and,

FIG. 8 is another perspective view of a light emitting diode package according to our new design.
